UNITED STATES PATENT OFFICE.

FRED C. IELFIELD, OF SILVER CREEK, NEW YORK.

MAIL-MARKING MACHINE.

1,136,960.

Specification of Letters Patent. Patented Apr. 27, 1915.

Original application filed March 22, 1913, Serial No. 756,191. Divided and this application filed June 12, 1913. Serial No. 773,163.

To all whom it may concern:

Be it known that I, FRED C. IELFIELD, a citizen of the United States, residing at Silver Creek, in the county of Chautauqua and State of New York, have invented new and useful Improvements in Mail-Marking Machines, of which the following is a specification.

This invention relates to a machine for canceling or post marking mail matter such as letters and post cards and has the objects to improve the means for separating one letter at a time from the supply stack of uncanceled letters and propelling the same past the printing device and to the stack of canceled letters.

This application is a sub-division of an application filed March 22, 1913, Serial #756,191.

In the accompanying drawings: Figure 1 represents a fragmentary top plan view of a mail marking machine embodying my improvements. Fig. 2 is a rear end elevation of the machine partly in section. Fig. 3 is a fragmentary vertical transverse section, on an enlarged scale, taken in line 3—3, Fig. 1.

Similar characters of reference indicate corresponding parts throughout the several views.

1 represents the horizontal table of the machine on the upper side of which are mounted the various parts which operate upon the letters or other mail matter and 35 on the underside of which are mounted the driving mechanism for operating the working parts of the machine.

The letters 2 to be canceled are arranged edgewise side by side on the supply portion 40 or section 3 of the table with their lower edges resting on the table and their front vertical edges engaging with a transverse wall 4 secured to the table while the foremost letter of the supply stack engages its 45 outer face against a rear longitudinal wall 5 secured to the upper side of the table adjacent to the inner end of the transverse wall the letters being only shown diagrammatically in this relation in Fig. 1 of the 50 drawings. Between the inner end of the transverse wall and the front end of the longitudinal wall is formed a gap or throat through which the letters are fed successively from the stack of uncanceled letters 55 to the printing device and the mechanism

which stacks the canceled letters on the receiving portion or section 6 of the table. The mechanism for thus separating one letter at a time from the supply stack and moving the same forwardly to the printing and 60 stacking mechanisms embodies several features of my invention and is constructed as follows:

7 represents a feed belt which passes with its front and rear turns around front and 65 rear pulleys or rollers 8, 9 and which has its operative stretch arranged lengthwise of the table above the upper side thereof and extending from the inner or delivery portion of the supply section of the table 70 forwardly through the throat between the inner end of the transverse wall and the front end of the longitudinal wall, thence past the printing mechanism and thence past the inner end of the receiving section 75 of the table. This feed belt comprises a main flat body portion 10 which is arranged vertically and a friction rib 11 having a flat face and arranged centrally and lengthwise on the outer side of the body portion 80 so as to form two longitudinal rabbets 12, 12 at opposite edges of the feed belt on the outer side thereof, as best shown in Figs. 2 and 3. The body of the feed belt and its rib may be constructed of any suitable material, the body consisting preferably of leather and the rib of rubber or similar material which will take a firm hold upon the letters when engaging therewith.

At the inner end of the transverse wall 90 the same is provided with an inwardly and forwardly inclined lip 13 the central portion 14 of which is thickened preferably by means of a plate to form a separator or separator jaw which projects beyond the inner 95 face of the lip, as shown in the drawings. At the inner or front end of this jaw the same is provided between its upper and lower edges with a notch or recess 15.

During the forward movement of the operative stretch of the feed belt its outer vertical side passes close to the front edge of the separator jaw while the rib of the feed belt projects into the notch or recess of this jaw. The effect of this is that while the 100 operative stretch of the belt passes forwardly with its rib in engagement with the flat outer side of the foremost letter of the supply section of the table this letter will be carried forwardly from the pile and 110

through the throat between the transverse and longitudinal walls, and while passing through this throat that portion of the letter engaged by the belt and the separator jaw will be crimped slightly by reason of the rib on the feed belt and the notched portion of the separating jaw forming a double kink in the letter or piece of mail matter. By this means the foremost letter is firmly gripped by the feed belt and materially stiffened so that the same will move forward reliably with the feed belt while the next following letter will be held back by the separating jaw and thereby insure the feeding of but one letter at a time from the supply stack to the printing and stacking mechanism.

The feed belt is normally retained in position so that its operative stretch always stands with the outer face of its body close to the front edge of the separating jaw and its rib projecting into the notch of this jaw, this being preferably effected by means of a retaining roller 16 engaging with the inner or back side of the feed belt transversely in line with the separating jaw. In order, however, to permit the feed belt to recede or give way and accommodate letters or pieces of mail matter of abnormal thickness this retaining roller is yieldingly mounted. For this purpose the retaining roller is preferably mounted by means of a vertical pivot on the front arm of a horizontally swinging retaining lever 17 which is pivoted by means of a pin 18 to a stationary part on the upper side of the table and this lever is constantly turned in the direction for moving the retaining roller against the inner or back side of the feed belt by means of a spring 19 interposed between the rear arm of the retaining lever and the adjacent outer side of the longitudinal wall, as shown in Figs. 1 and 2.

The movement of the retaining roller toward the separating jaw is limited so as to prevent this roller from pressing the feed belt against the separating jaw and wearing the same unduly, the preferred means for thus limiting the movement of the retaining roller consisting of an adjustable stop screw 20 arranged on the front arm of the retaining lever and bearing against the outer side of the longitudinal wall, as shown in Fig. 1.

The thickness of the rib on the feed belt is less than the depth of the notch in the separator jaw so that the belt may be adjusted very closely to the separator and even engage the same without liability of engaging the outer face of its rib with the bottom of said notch. By this means the feed belt may be so adjusted that the face of the rib is in line or substantially so with the rear edge portions of the separator above and below its notch and the letter engaged at

three staggered points without producing a crimp in the same which is desirable for feeding very thin letters or other mail matter, or the rib may be adjusted to a greater or lesser extent into the notch of the separator for crimping the letters or mail matter and obtaining a firmer grip on the same, this last mentioned arrangement being more suitable for thick or heavy mail matter. By this means the feed belt can be adjusted to the separator to suit the character of the particular mail matter which is to be post marked without the possibility of the face of the rubber rib being dragged in contact with the separator, thereby avoiding undue wear of the latter and maintaining the same for a long time in a condition in which the same will properly grip the letters and feed the same forward one at a time past the separator before requiring renewal of this rib. Interruption in the operation of the machine and cost of keeping the same in repair is therefore reduced to a minimum.

The front and rear pulleys of the feeding belt are mounted on the upper ends of an upright shaft 21, 22 which are journaled in suitable bearings arranged on the adjacent part of the table and may be driven by any suitable means.

As each letter issues from the throat of the supply section of the table the same is first intercepted by a timing device having an intermittently retractable stop 23 which prevents the continued forward movement thereof unless the printing mechanism is in the proper position to receive the same and thereafter the printing mechanism operates upon the letter to produce a post mark or canceling stamp thereon. This printing mechanism may comprise a printing wheel 24 and an impression roller 25 which are arranged on opposite sides of the path of the letters as they issue from the feed throat.

As the letters issue successively from between the members of the printing couple they are operated upon by means of a stacking device which pushes the same laterally away from the feed belt upon the receiving section of the table, this stacking device consisting preferably of a plurality of cam arms 26 arranged on the shaft of the delivery pulley or a part turning therewith.

I claim as my invention:

1. A mail marking machine comprising a relatively fixed separator having a notch in its operative edge, and an endless feeding belt having the upper and lower parts of its face moving past the edge of said separator above and below said notch and provided between the upper and lower parts of its face with a continuous friction rib which passes through the notch of said separator.

2. A mail marking machine comprising a

relatively fixed separator having a notch in its operative edge, and an endless feeding belt having the upper and lower parts of its face moving past the edge of said separator above and below said notch and provided between the upper and lower parts of its face with a continuous friction rib which passes through the notch of said separator, the depth of said notch being greater than 10 the distance from the face of said rib to the face of said feeding belt.

3. A mail marking machine comprising a feeding table, a printing mechanism, a stacking device, a separator arranged between the feeding table and the printing mechanism and provided in its operative edge with a notch, and an endless feeding belt passing along said feeding table, printing mechanism and stacking device and having 20 the upper and lower parts of its face arranged close to the parts of the operative edge of said separator above and below the notch thereof, and a continuous friction rib arranged lengthwise on the face of said belt between the upper and lower parts thereof, and a time stop which is arranged between said 25 separator and said printing mechanism and which is adapted to control the forward movement of the letters in harmony with said printing mechanism.

4. A mail marking machine, comprising a feeding table, a printing mechanism, a stacking device, a separator arranged between the feeding table and the printing mechanism and provided in its operative edge 30 with a notch, an endless feeding belt passing along said feeding table, printing mechanism and stacking device and having the upper and lower parts of its face arranged close to the parts of the operative edge of 35 said separator above and below the notch thereof, a continuous friction rib arranged lengthwise on the face of said belt between the upper and lower parts thereof, and a time stop which is arranged between said 40 separator and said printing mechanism and which is adapted to control the forward movement of the letters in harmony with said printing mechanism.

Witness my hand this 9th day of June, 45
1913.

FRED C. IELFIELD.
